UNITED STATES PATENT OFFICE.

MORRIS J. HOFFMAN, OF CHICAGO, ILLINOIS.

GARMENT-SHAPER.

1,142,431.

Specification of Letters Patent. Patented June 8, 1915.

Application filed August 24, 1914. Serial No. 858,251.

To all whom it may concern:

Be it known that I, MORRIS J. HOFFMAN, a citizen of the United States, and a resident of Chicago, county of Cook, and State 5 of Illinois, have invented certain new and useful Improvements in Garment-Shapers, of which the following is declared to be a full, clear, and exact description.

This invention relates to garment shaper, 10 and its primary object is to provide a device of simple construction for use in stretching the shoulder portion of coats and vests so as to give proper shape to them at hollow places at the shoulders.

15 To such ends this invention consists in the several novel features hereinafter described and claimed.

The invention is clearly illustrated in the accompanying drawings in which:

20 Figure 1 is a perspective view of a garment shaper embodying a simple form of the invention; Fig. 2 is a rear view of the stretching forms; Fig. 3 is a plan of the upper form; Fig. 4 is a plan of the lower 25 form; Fig. 5 is a vertical section taken through the upper and lower forms, the line of section being indicated at 5—5 in Figs. 3 and 4; Fig. 6 is a similar section showing the parts in a different position; Fig. 7 is 30 a vertical, detail section taken on line 7—7 of Fig. 3; and Fig. 8 is a detail section showing certain felt covering for the forms.

Referring to said drawings, 10, designates a table, at the rear of which is a 35 lower stationary form 11, above which is an upper, movable form 12. Preferably the two are pivoted together, as, for instance, by hinges 13, secured at the rear edges of the forms.

40 Means are provided for heating the lower form, and in the simple arrangement shown, said form is made hollow to receive a gas burner 14, although if desired steam may be admitted to the hollow of the form to 45 supply the necessary heat. The faces 15, 16 of the forms are the working faces between which the portion of a garment to be operated on is placed, and the face of one form, for instance the lower form, has a 50 recessed portion 17, which slopes down toward the rear edge of the form; it is curved in cross section, and merges into the flat face of the form. The recessed portion 17 extends crosswise of the form and other recessed portions 18, 19, similar in character, 55 but extending lengthwise of the form may be provided, if so desired.

Associated with the upper form and opposite to the recessed portion 17, is a stretching member or block 20, which is 60 connected with the upper form, as for instance, by pivot pin 21. The upper form has an opening or recessed portion 22, for receiving the stretching member, and the lower face 23 of the stretching member is 65 shaped to correspond with the contour of the recessed portion 17 of the lower form, and fitting thereinto during a certain portion of the operation of the device. Other stretching members or blocks 24, 25, may be 70 provided on the upper form above the recessed portions 18, 19, and if desired they may be made integral with the upper form or pivoted thereto in the manner of the stretcher 20.

75 Means are provided for raising and lowering the upper form and for raising and depressing the stretching members. In the simple arrangement shown for accomplishing this result, two upright links or bars 26, may be used, said bars being preferably connected at the top and bottom by cross bars 27, 28, and the lower cross-bar connected to a treadle 29, by a rod 30. A coiled tension spring 30^a secured to the 80 lower form and rod 30 acts to raise the upper form. The upper cross-bar 27 extends across the upper form and across the stretching members and the upright bars 26, are connected to the ends of the upper 85 form by pins 31, secured to bars 32, that are fastened to the upper form. The pins 31, enter vertical slots 33 in the bars 26, and compression springs 34 are interposed between said pins and the upper ends of the 90 slots. When in raised position the pins rest in the bottom of the slots and whenever the treadle is moved down the upper form is lowered and pressed down upon the lower 95 form or piece of garment laid thereon, the 100 springs 34 permitting a slight amount of lost motion before the cross bar 27 strikes the stretching members and depresses them. Said stretching members are shown as sustained from the cross-bar 27, by headed eye 105 bolts 35, secured to the stretching members by staples 36, and extending through staples or eye bolts 37, secured to the cross-bar 27. When the upper form is raised the head of the bolt 35 rests on the staple or eye-bolt 37, 110

thus sustaining the stretching member; and permitting the cross-bar and upper form to move down toward the lower form before the cross-bar begins to depress the stretching members.

Means are provided for smoothing the cloth and preventing wrinkling thereof while the upper form is being lowered upon the cloth, and a simple means comprises two smoothing members, here shown in the form of oppositely moving fingers, 38, one at each side of the stretching block, 20 (see Figs. 3 and 5), pivotally secured in recesses in the lower face of the form 12, and spring 10 pressed in a downward direction by springs 39. Said smoothing fingers project away from each other and downward, as shown, and while the form is being lowered, their ends press against the cloth on both sides of 15 the recessed portion 17, and swing away from each other thereby smoothing the cloth over said recess. The smoothing fingers move back into the recesses in which they are pivoted, while the form 12 is being lowered, so that when fully lowered, their lower 20 faces are flush with the lower face of the upper form. Preferably the under faces of the smoothing fingers 38, are roughened or serrated to enable them to take a firm hold 25 on the cloth.

If desired the working faces of the forms and stretching members may be covered with felt or other suitable fabric as seen at 40 in Fig. 7, and held in place by strips of metal 35 41, screwed to the forms and stretching members.

In the operation of this device the lower form is first heated to the desired temperature and the piece of the cloth (A) to be 40 stretched, is laid on the lower form with its upper edge, a, placed as far back as it will go between the two forms. The treadle is then depressed and the upper form therewith lowered upon the cloth, clamping it tightly between the two forms, the two smoothing fingers 38, simultaneously stretching the cloth over the recessed portion 17, as the upper form approaches the lower one. Continued 45 downward movement of the treadle compresses the springs 34, and puts more pressure on the cloth, and at the same time the cross-bar 27 comes down upon the stretching members and depresses them, thereby forcing down the portions of the material lying 50 over the recessed portions 17, 18, 19, into said recessed portions and smoothing those 55 portions. The parts are held in this position for sufficient time to effect the stretching of the piece and the foot is then taken off the treadle, the spring 30^a lifting the links and therewith the upper form and the stretching blocks.

With this device unskilled operators may 60 give the garment the right amount of stretching and at the proper places.

Various alterations and modifications of the form of the invention are possible without departing from the spirit of this invention and I desire, therefore, not to limit myself to the exact form of construction shown 70 and described, but intend in the following claims to point out all of the invention disclosed herein.

I claim as new and desire to secure by Letters Patent:

1. A garment shaper, comprising two companion forms for clamping between them a part of a garment, one movable toward and away from the other, the working face of one form having a recessed portion, and the 80 working face of the other form having an opening therein, and a stretching member movably mounted in said opening and adapted to enter said recessed portion and therewith stretch that part of a garment overlying 85 said recessed portion.

2. A garment shaper, comprising two companion forms having opposing working faces between which a part of a garment is clamped, one form movable toward and away from the other, one of said forms having a recessed portion in its working face, and the other form having a stretching member fulcrumed in an opening therein and adapted to enter said recessed portion, 90 and means for actuating the movable form and stretching member carried thereby.

3. A garment shaper, comprising two companion forms, having opposing working faces, and one pivoted upon the other, one form having one or more recessed portions in its working face, and the other form having a corresponding number of stretching members movably mounted thereon, and adapted to enter said recessed portions and means for bringing one form down upon the other, and for depressing the stretching members into the recessed portions and therewith stretching that part of a garment 100 overlying the recessed portions.

4. A garment shaper, comprising two forms, one being stationary and having a recessed portion in its upper face, and the other pivoted thereto along an edge and arranged to be swung down thereupon, said movable form having a stretching block pivotally secured in an opening therein opposite the recessed portion of the stationary form, and arranged to be depressed into said 105 recessed portion.

5. A garment shaper, comprising a stationary form, and a movable form hinged thereto along one edge, one of said forms having a recessed portion in its working face and the other form having a stretching block pivotally secured in an opening therein, and arranged to be depressed into said recessed portion of the other form, and means for actuating said movable form and stretching block.

6. A garment shaper, comprising a stationary form, and a movable form hinged thereto along one edge, one of said forms having a recessed portion in its working face and the other form having a stretching block pivotally secured in an opening therein, a treadle and connection between the movable form, stretching block and treadle.
7. A garment shaper, comprising a stationary form, and movable form hinged thereto along one edge, one of said forms having a recessed portion in its working face and the other form having a stretching block pivotally secured in an opening therein, a treadle, a pair of links connected to said treadle and to said movable form, there being a slight amount of lost motion in the connection with the movable form, and means moving with said links for actuating the stretching block.
8. A garment shaper, comprising a stationary form, and a movable form hinged thereto along one edge, one of said forms having a recessed portion in its working face and the other form having a stretching block pivotally secured in an opening therein, a cross bar extending across said movable form and stretching block and means for raising and lowering said cross bar and therewith raising and lowering the movable form and stretching block.
9. A garment shaper, comprising a stationary form, and a movable form hinged thereto along one edge, one of said forms having a recessed portion in its working face and the other form having a stretching block pivotally secured in an opening therein, means for depressing the movable form to press the garment tightly between the two forms and thereafter depressing the stretching block into the recessed portion of the lower form.
10. A garment shaper, comprising a stationary form having a flat working face formed with a recessed portion, means for supplying heat to said form, a movable form associated therewith and having a flat working face arranged to press against the flat face of the stationary form, a stretching block pivotally connected to said movable form and adapted to enter said recessed portion of the stationary form, and means for actuating said movable form and stretching block.
11. A garment shaper, comprising a stationary form, a movable form thereabove, one of said forms having a recessed portion in the face opposing the other form, and said other form having a stretching block arranged to be depressed into said recessed portion, and two diverging smoothing fingers, movably secured to the movable form, one finger being located at each side of said stretching block and arranged to engage the cloth to be stretched, and smoothen the same across the recessed portion while the movable form approaches the stationary form.
12. A garment shaper comprising a stationary form and a movable form hinged thereto at one edge, the stationary form having a recessed portion in its working face, a stretching block carried by the movable form and arranged to be depressed into said recessed portion, a pair of smoothing fingers, one on each side of said block and pivotally secured to said movable form, said fingers extending toward the stationary form on oblique lines, away from each other, and springs for yieldingly pressing said fingers toward the stationary form.
13. The combination of two relatively movable, clamping forms, the clamping faces of which are flat in the main portions and between which the material to be stretched is adapted to be clamped in a flat condition, a garment stretching member carried by one of said forms, and garment smootheners, one at each side of the garment stretching member, said garment smootheners being carried by one form and co-acting with the other form to smoothen the material, at least one of them having a pushing action along the face of the material in a direction away from the other smootheners.
14. The combination of two relatively movable forms having flat plane faces between which part of a garment is clamped, one of said forms having a garment stretching member, and two oppositely moving smoothing fingers, one on each side of the stretching member and pivoted to the form having the stretching member, and co-acting with the other form to smoothen the garment.
15. The combination of two members having flat plane faces between which a part of a garment is clamped, and two garment smootheners secured to one of said members and co-acting with the other form to smoothen the garment, at least one of said garment smootheners moving in a direction away from the other while the forms are being brought together to clamp the garment therebetween.
- In witness whereof I have hereto executed the above instrument at Chicago, Illinois, this 20th day of August, A. D. 1914.
